UNITED STATES PATENT OFFICE.

GEORGE FREUND, OF DURANGO, COLORADO.

DESIGN FOR A SPOON.

SPECIFICATION forming part of Design No. 22,406, dated May 9, 1893.

Application filed April 3, 1893. Serial No. 468,938. Term of patent 7 years.

To all whom it may concern:

Be it known that I, GEORGE FREUND, of Durango, in the county of La Plata and State of Colorado, have invented a new and original 5 Design for a Spoon, of which the following is a full, clear, and exact description.

The design consists in the surface ornamentation in the bowl of the spoon as shown in accompanying drawing, in which the figure 10 is a front view of a spoon embodying my new design.

The design represents a bird's eye view, in which appears a river, having a winding course and crossed by several bridges. In 15 the foreground appears a series of buildings

of the general form of smelting works, together with a railroad with a train thereon, and a round-house. In the middle distance, beyond the river, both to the right and left of the scene, appear additional smelting 20 works, with smoking chimneys, and in the back ground mountains appear, as shown.

I claim—

The design for a spoon herein shown and described.

GEORGE FREUND.
